UNITED STATES PATENT OFFICE.

ERNEST J. SCHWEITZER AND ROBERT G. WAGNER, OF LOS ANGELES, CALIFORNIA.

DESIGN FOR A LIGHTING-FIXTURE.

48,400.

Specification for Design.

Patented Jan. 4, 1916.

Application filed October 28, 1915. Serial No. 58,495. Term of patent 3½ years.

To all whom it may concern:

Be it known that we, ERNEST J. SCHWEITZER and ROBERT G. WAGNER, citizens of the United States, residing at Los Angeles, in the county of Los Angeles and State of California, have invented a new, original, and ornamental Design for a Lighting-Fixture, of which the following is a specification, reference being had to the accompanying drawing, forming part thereof.

The figure is a side elevation of the fixture.

We claim:

The ornamental design for a lighting fixture, as shown.

ERNEST J. SCHWEITZER.
ROBT. G. WAGNER.

Witnesses:

FREDERICK S. LYON,
ANNA F. SCHMIDTBAUER.
